UNITED STATES PATENT OFFICE.

RALPH THEW BRANKSTON, OF NEWCASTLE-UPON-TYNE, ENGLAND, AS-
SIGNOR TO W. G. ARMSTRONG, WHITWORTH & COMPANY, LIMITED,
OF NEWCASTLE-UPON-TYNE, ENGLAND.

GUN-MOUNTING.

SPECIFICATION forming part of Letters Patent No. 695,087, dated March 11, 1902.

Application filed October 14, 1901. Serial No. 78,605. (No model.)

To all whom it may concern:

Be it known that I, RALPH THEW BRANKSTON, engineer, a subject of the King of Great Britain, residing at Elswick Works, Newcastle-upon-Tyne, England, have invented a certain new and useful Gun-Mounting, of which the following is a specification.

The object of this invention is to provide a convenient method by which a high angle of elevation can be obtained and at the same time the gun can be placed low down in order that the center of gravity may be as low as possible when traveling. The usual method to obtain high elevations with large guns is to employ an upper carriage, which is fixed to the upper side of the trail; but this involves the erection of a gin or shear-legs and the dismounting of the gun and the removal of the wheels from the carriage; but by means of this invention the gun can be wheeled up into position and the full elevation can be obtained in a few minutes without the aid of shear-legs or gin, which may be conspicuous objects at an inconvenient time.

At each side of the carriage is a lever pivoted to the axle and having its rear end pivoted to the trail. The lever has pivoted to it a block, forming a bearing for supporting the lower end of a shaft, whose upper end is screw-threaded and works in a nut pivoted to the front of the trail. This shaft can be revolved by means of a worm mounted in bearings in the block, which gears with a worm-wheel fixed to it.

Figures 1 and 2 are side elevations of a gun carried by a gun-mounting constructed according to this invention. The sights and other details not connected with the invention are omitted. In Fig. 1 the gun is shown in its lower or traveling position and in Fig. 2 in its high position. Fig. 3 shows a detail. The dotted lines indicate the maximum angles of elevation which can be given to the gun when in these positions. In Fig. 1 it is about thirty degrees and in Fig. 2 fifty degrees.

a is the gun, free to recoil in a cradle *b* in the ordinary manner.

b' represents trunnions fixed to the cradle

b and working in bearings at the front of the trail *c*.

d is a lever pivoted at *d'* to the trail and to the axle *e'* of the carrying-wheels *e*. The front end of the lever *d* is connected by a link *d''* to a brake-block *f*, which can be jammed against the wheel *e* by the handle *f'*.

g is a block pivoted at *g'* to the lever *d* and forming a bearing for the lower end of the shaft *h*.

j is a worm mounted in bearings in the block *g* and gearing with a worm-wheel *h'*, fixed to the shaft *h*. The spindle of the worm *j* has a square end *j'* to receive a handle by which it can be turned.

k is a nut on the screw-threaded shaft *h*, which is pivoted at *h'* to the front end of the trail.

The gun, whether in its lower position, Fig. 1, or in its upper position, Fig. 2, is elevated and depressed in the ordinary manner by a curved-rack *b''*, fixed to the cradle *b*, and a pinion *c'*, mounted in bearings in the trail.

In order to prevent side strains in traveling, each of the trails *c* has fixed to its under side a segment *c''*, wedge-shaped in cross-section, which engages with corresponding flanges *d''* on the lever *d*, as is clearly shown in Figs. 1 and 3.

What I claim is—

1. In a gun-mounting the combination of an axle, carrying-wheels on the axle, a trail, a lever connecting the trail to the axle, and means for varying the angle between the lever and trail.

2. In a gun-mounting the combination of an axle, carrying-wheels on the axle, a trail, a lever connecting the trail to the axle, a screw-threaded shaft pivoted to the lever, a nut on the shaft pivoted to the trail, and means for rotating the shaft.

3. In a gun-mounting the combination of an axle, carrying-wheels on the axle, a trail, a lever connecting the trail to the axle, a screw-threaded shaft pivoted to the lever, a nut on the shaft pivoted to the trail, a worm-wheel fixed to the shaft, and a worm pivoted to the lever gearing with the worm-wheel.

4. In a gun-mounting the combination of an

RALPH THEW BRANKSTON.
